UNITED STATES PATENT OFFICE.

EDMOND EUSTACHE RENÉ GAUDART, OF PARIS, FRANCE.

APPARATUS FOR HUSKING EARTHNUTS AND THE LIKE.

1,323,043.

Specification of Letters Patent. Patented Nov. 25, 1919.

Application filed October 22, 1918. Serial No. 259,187.

To all whom it may concern:

Be it known that I, EDMOND EUSTACHE RENÉ GAUDART, citizen of the Republic of France, residing at 12 Avenue Trudaine, 5 Paris, Seine, in the Republic of France, have invented new and useful Improvements in Apparatus for Husking Earthnuts and the like, of which the following is a specification.

10 This invention has for its object to provide an improved apparatus more particularly adapted for husking earth-nuts. The improved apparatus consists substantially of a fixed drum with a vertical axis and 15 having the shape of a truncated ellipsoid. This drum is traversed axially by a shaft that carries on one portion of it a screw having an ellipsoidal core situated inside the drum, and on another portion of it a plate 20 or disk situated a short distance below the lower edge of the drum.

The drum is composed of a number of parts assembled along equatorial or meridian planes with intermediate spaces the 25 width of which can be adjusted at will by interposing spacing pieces of suitable thicknesses.

When the screw is set in motion, the earth-nuts are charged in small quantities 30 into an upper hopper. These nuts pass slowly through the drum, and during their descent are continually thrown against its walls, and the repeated shocks to which the nuts are subjected effect the husking of the 35 nuts. The husks which are projected outward pass through the intermediate spaces provided between the parts of the drum, and the kernels drop upon the lower revolving plate or disk whence they are led into a 40 collecting hopper. The light particles and the dust collect around the screw and are discharged at the top by passing through the interior of the core if the latter is hollow and perforated.

45 The improved apparatus is also suitable for depulping or crushing certain fruits or nuts.

In the particular case of crushing, the screw may be adapted to be raised or 50 lowered in such a manner as to reduce the free space between it and the drum within a certain zone.

The manner in which this invention is to be performed will now be more particularly

described with reference to the accompanying drawings, which illustrate by way of example a constructional form of the improved apparatus. In these drawings:

Figure 1 is a vertical section of the improved apparatus on the line 1—1 of Fig. 60 2 and

Fig. 2 is a side elevation thereto.

In the constructional form shown, the improved apparatus comprises essentially a fixed drum *a* having a vertical axis, and 65 shaped approximately in the form of a truncated ellipsoid. The drum is composed of a number of assembled annular parts that are superposed and connected together by means of lugs *b* with interposed packing 70 pieces *c* which by their thickness serve to adjust the width of the empty intermediate spaces *d*.

The drum *a* is traversed axially by a shaft *e* which may be driven in any suitable manner at a speed of about 200 to 300 revolutions per minute. This shaft carries a screw *f* having an ellipsoidal core that may be solid as shown at *g*, or may consist of a casing of perforated sheet metal or of metal 80 lattice-work. At a short distance from the lower edge of the drum *a*, the shaft *e* has keyed on it a plate *h* having inclined edges. A lever *i* that can be fixed in any desired position, allows of adjusting the shaft *e* and 85 consequently the screw *f* and the plate *h* relatively to the drum *a*.

When the screw *f* has attained its normal speed the earth-nuts are charged in small quantities into the hopper *j*. These nuts 90 are carried around by the rotating screw *f* and are projected by centrifugal force against the sides of the drum. The nuts are gradually broken and freed from their husks which is projected through the intermediate spaces *d*. The kernels drop on to the plate *h* and are collected in a hopper. The dust and light particles collect around the screw, and may be discharged at the top by the current of air caused by the rotation of the screw, or through the interior of the core *g* when the latter is hollow and perforated as hereinabove stated.

It is to be noted that any nuts that reach the lower end of the drum without being 105 husked, are unable to pass out through the space left between the lower edge of the drum and the plate *h*, so that the said un-

husked nuts will accumulate on the plate λ and will be returned by the screw to the top of the drum.

Having now described my invention what 5 I claim as new and desire to secure by Letters Patent is:

1. An apparatus for husking fruit, grains and nuts comprising in combination a vertical casing open at both ends having a 10 smooth inner surface and provided with spaced horizontal slots affording a communication from the inside to the outside of said casing, a core supported axially in said casing, a helical rib on the periphery of said 15 core, means for rotating said core and means for closing the lower end of the casing with the exception of a narrow peripheral slot.

2. An apparatus for husking fruit, grains and nuts, comprising in combination a vertical casing open at both ends and having the shape of a truncated ellipsoid, said casing being provided with spaced horizontal slots affording a communication from the inside to the outside of said casing, an ellipsoid shaped core supported axially in said casing, a helicoidal projecting ridge on said core, means for rotating said core, feeding 25 means mounted on the casing at the upper end thereof and a disk having an inclined 30 upper surface and supported at a short distance from the lower edge of the casing.

3. An apparatus for husking fruit, grains and nuts comprising in combination a vertical casing open at both ends and having the shape of a truncated ellipsoid, said casing being made up of annular parts secured 35 one upon the other with intervening spacers therebetween, which form through the casing wall spaced horizontal slots affording

a communication from the inside to the outside of the casing, a rotary shaft, means for supporting said shaft axially in said casing, an ellipsoid shaped core on said shaft, a helicoidal projecting ridge on said core, means for rotating said shaft, feeding 40 means mounted on the casing at the upper end thereof, and a disk having an inclined upper surface and secured on the shaft at a short distance from the lower edge of the casing.

4. An apparatus for husking fruit, grains and nuts comprising in combination a vertical casing open at both ends and having the shape of a truncated ellipsoid, said casing being made up of annular parts secured one upon the other with intervening spacers therebetween, which form through the casing wall spaced horizontal slots affording a communication from the inside to the outside of the casing, a rotary shaft, means for supporting said shaft axially in said casing, an ellipsoid shaped core on said shaft, a helicoidal projecting ridge on said core, means for rotating said shaft, feeding means 50 mounted on the casing at the upper end thereof, a disk having an inclined upper surface and secured on the shaft at a short distance from the lower edge of said casing and means for displacing the shaft longitudinally.

In testimony whereof I have signed my name to this specification in the presence of two subscribing witnesses.

EDMOND EUSTACHE RENÉ GAUDART.
